UNITED STATES PATENT OFFICE.

EUGEN JOHANNES MANKIEWICZ, OF HAMBURG, GERMANY.

HAND-STAMP FOR INDORSING, &c.

SPECIFICATION forming part of Letters Patent No. 741,520, dated October 13, 1903.

Application filed June 20, 1901. Serial No. 65,811. (No model.)

To all whom it may concern:

Be it known that I, EUGEN JOHANNES MANKIEWICZ, a subject of the Emperor of Germany, residing at Hamburg, in the Empire of Germany, have invented certain new and useful Improvements in a new or Improved Hand-Stamp for Indorsing and the Like, of which the following is a full, clear, and exact description.

This invention consists of a new or improved hand-stamp the special feature of which is that a number of different stamping-plates are so arranged on an endless band or hinged together in series that the particular stamp which it is desired to use can be readily brought into position and its designation observed by means of an indicator.

A further feature is an automatic inking device which inks the particular stamp in use while it is in the act of descending within its casing, as hereinafter set forth.

The accompanying sheet of drawings illustrates the invention, Figure 1 being a front elevation; Fig. 2, a section on line A A of Fig. 1, showing the inking-roller and stamp in its normal position of rest; and Fig. 3, also a section on line A A of Fig. 1, but showing the stamp in its position while actually giving the impression. Fig. 4 is a side view of the whole device seen from outside, and Fig. 5 an arrangement for controlling the movement of the endless band.

The casing within which the stamp works consists of an upper part *a*, in combination with a lower part *b*, into which it is adapted to slide by a telescope action. Upon the movable part *a* are mounted two parallel rollers *c d*, over which is arranged an endless band or the like carrying stamping-plates 1, 2, 3, 4, &c., bearing any suitable and various denominations. Each stamping-plate is repeated or indicated upon a register or indicator *h*, and an endless chain *f*, passing over toothed wheels on the axles of the two rollers aforesaid, carries a pointer *g*, which not only serves to rotate the endless band and bring any desired stamp into position, but also indicates by its position on the register or indicator the exact stamp which is for the moment ready for impressing. The wheels of the rollers over which the chain *f* passes are so proportioned to the diameter of

the rollers *c d* that the whole series of stamping-plates can make a complete circuit while the pointer *g* simply moves from the top to the bottom of the indicator or register *h*, for which purpose one of the toothed wheels over which the chain passes must be an idle wheel. The rollers *c d* are, as will be seen, flattened into hexagonal or similar form suited to the stamping-plates.

In order to efficiently stop the bottom roller when a stamping-plate has been brought into position and prevent the same from revolving further or accidentally becoming displaced, a nut *t* is fixed upon the end of the axle of similar section to the roller and a pair of flat spring-arms *v* bear against the same, thus producing a restraining effect. If the spring-arms themselves be of rigid material, they may be arranged scissorwise, with a compression-spring *u* between their ends.

The inking of the particular stamp about to be used is done by an inking-roller *l*, mounted between the extremities of the long arms 75 of a pair of bell-crank levers *k*, hinged to a pivot-rod *i*, lying across the lower casing *b*, so that every time the upper casing *a* is forced down the roller *l* inks the bottom stamping-plate. The short arms of the bell-crank levers carry a wheel *m*, which is continually pressed upon by springs *n*, fixed into the back of the lower casing *b*. The arrangement of the inking-roller *l* is such that while the complete hand-stamp is not in the act of stamping said roller *l* remains immediately behind the stamping-plate waiting to be inked. At the extreme ends of the roller are two raised rims *o*, of elastic material, which bear against the lower edges of the upper casing *a*. Upon the lowering of the latter the roller *l* rotates by reason of the rolling of the elastic rims *o* upon the lower edges of the upper casing *a* and rolls under pressure of springs *n* upon the under surface of the stamping-plate, thus 85 inking the latter. When the inking of the plate is over, the further descent of the upper casing *a* causes the inking-roller to continue its horizontal movement along the bottom edge of the walls *a* of the upper casing 90 and to ride upon its elastic rims around the corner and up along the side edges, when its arm will be in a vertical position, as shown by Fig. 3. After the stamping has been per-

formed the pressure upon the upper casing is released, when the springs *n* return the arms *k* to their original position (shown in Fig. 2) by bearing upon the wheels *m*, carried by short arms of bell-crank lever *k*, and the upper casing rises to its full height under the influence of springs *r*, situated between it and the lower casing *b*.

The manner of using the apparatus is, 10 briefly, as follows: Should it be desired to use the stamp No. 7, for example, the endless chain *f* is rotated by means of the pointer *g* being traveled up or down until it is opposite the space 7 on the indicator. When this is 15 done, the corresponding stamp 7 is at the bottom of the series in position for use.

What I claim, and desire to secure by Letters Patent, is—

1. In a hand-stamp for indorsing and the 20 like of the kind in which a series of printing-surfaces is arranged in an endless band, the combination of two rollers *c* and *d*, of an indicator or register *h* on the outside of the apparatus, an endless chain *f* passing over 25 toothed wheels, one of said wheels being fixed on the axle of one of said two rollers, and a pointer *g* carried by the said chain adapted

to indicate or readily bring into position any desired stamping-plate, the whole substantially as described with reference to the drawings. 30

2. In a hand-stamp for indorsing and the like, the combination of an endless band bearing stamping-surfaces, two parallel rollers over which said band is arranged, a toothed 35 wheel at the extremity of one of said rollers, a chain *f* passing over said toothed wheel for the purpose of rotating said rollers, together with said band when desired, a pointer *g* fixed on the chain and an indicator *h* upon the casing, the diameter of the toothed wheel aforesaid being so proportioned to the corresponding roller that the whole series of printing-surfaces on the endless band are capable of being brought into proper position for printing by the single traverse of the pointer from 40 the top to the bottom of the indicator, the whole substantially as described. 45

In witness whereof I subscribe my signature in presence of two witnesses.

EUGEN JOHANNES MANKIEWICZ.
